UNITED STATES PATENT OFFICE.

JOSEPH G. PROSSER, OF CHICAGO, ILLINOIS, ASSIGNOR TO PARAMOUNT HOSIERY FORM DRYING CO., OF CHICAGO, ILLINOIS, A CORPORATION OF ILLINOIS.

HOSIERY-FINISHING APPARATUS.

1,268,066.

Specification of Letters Patent. Patented May 28, 1918.

Application filed April 6, 1918. Serial No. 227,639.

To all whom it may concern:

Be it known that I, JOSEPH G. PROSSER, a citizen of the United States, residing at Chicago, in the county of Cook and State of Illinois, have invented certain new and useful Improvements in Hosiery-Finishing Apparatus, of which the following is a specification, reference being had therein to the accompanying drawing.

10 This invention relates broadly to hosiery finishing apparatus and more especially to structures for drying and shaping so-called "full-fashioned" hosiery.

Generally defined, "full-fashioned" hosiery is a type which is knit in sheet form—as distinguished from tubular knitting—and according to a particular shape which the goods will assume when the seam-edges are sewed together. When that is done, a 15 seam extending from the toe to the top of the stocking is made. Prior to the invention of John H. Brine, as covered in United States Patent No. 1,218,520, granted March 6, 1917, it was usually the practice to board 20 "full-fashioned" hosiery on solid drying forms in such a manner that "rights" and "lefts" were produced; this name arising from the fact that the seam would, by the boarding, be thrown to the right or the left 25 of a longitudinal line.

More or less satisfactory results have been secured by the use of the aforementioned Brine invention; but I have devised certain improvements which, in practical 30 use, have proved to be of considerable importance. I have found that, instead of seating the hosiery seam in an edge-groove as is contemplated in the aforementioned Brine patent, novel and unexpected results 35 have been achieved by lining the seam upon a flattened surface at the edge of a drying and shaping form, the point thereof being to shape the seam into a crease formation.

It is, therefore, the object of my invention to provide, in a drying and shaping form, a surface so formed and related to the sides of that form that the seam shall, itself, be formed up into a crease of relatively reduced thickness.

50 To this end, I provide a drying and shaping structure which has its front portion with a crease-producing edge, while the op-

posite edge is flattened to produce a seam-engaging surface whereby the seam of the goods is internally lined up and set with 55 a crease formation, the setting resulting from the ironing effect of the edge of the form on the seam and the rapid evaporation of the moisture in the seam.

In order that my invention may be readily comprehended, I append hereto drawings which are intended to be illustrative of one practical and preferred embodiment of the invention; it being understood, however, that this may be considerably modified 60 without departing from the principle of the invention or sacrificing any of its advantages.

In these drawings,

Figure 1 is a view in perspective of an 70 internally-heated hosiery-drying and shaping form with a "full-fashioned" stocking superposed thereon, a portion of the latter being cut away to disclose, first, the seam-engaging surface of the form and, also, the 75 relation thereto of the seam of the goods;

Fig. 2 is a fragmentary view in transverse section thereof; and

Fig. 3 is likewise a fragmentary view on a very much larger scale.

Referring to the drawings, it will be noted that the reference-numeral 1 indicates a stocking of the so-called "full-fashioned" type. This is shown as formed with a seam 2 at the rear, this extending from the toe to 85 the top of the stocking.

In order that this type of hosiery may be efficiently and satisfactorily dried, shaped and finished, I have provided a hollow form 3 which is adapted to be heated by passing 90 a thermal fluid therethrough. Preferably and as shown, this form has arc-shaped sides 4, these being shaped to present oppositely-bulged fabric-flattening surfaces which converge and terminate in a relatively reduced 95 crease-producing edge 5 which has the function to crease, shape and finish the front portion 6 of the stocking.

The side surfaces of the form likewise converge at its opposite portion; but, in this 100 instance, instead of terminating in a crease-producing edge, like the edge 5, this opposite edge is flattened to present a seam-engaging surface 7 extending longitudinally

of the form from near its top 8 to a point adjacent to the base 9. The seam-engaging surface 7 is preferably and as shown of greater width than the surface at the edge 5 but of considerably less width than the thickness of the middle portion of the form. It, therefore, follows that the sides of the forms are disposed so that they intersect the plane of the seam-receiving edge and that they extend at an angle thereto and outwardly therefrom.

When a stocking is placed upon a form constructed in accordance with my invention, the seam will be readily and actually lined up on the seam-engaging surface; and, by reason of the incidental stretching of the fabric as it is placed upon the form and the position of the seam-engaging surface with respect to the sides of the form, the seam of 20 the goods is lined up into a crease or crease-formation that will be exactly opposite to the crease formed in the opposite side of the goods by the crease-producing edge 5 of the form. In consequence, the hosiery is given 25 a single crease-formation at its front and rear, the crease-formation at the seam being not greatly if any out of proportion to that at the front of the goods.

From the above description, it will be seen 30 that I have provided a hosiery-finishing form of a novel construction and one par-

ticularly adapted to produce satisfactory crease-formations at its front and rear.

What I claim is:

1. A drying and shaping structure for 35 treating hosiery including a hollow form to contain a heating medium and having its front portion provided with a crease-forming edge, the opposite edge being flattened to present a seam-engaging surface whereby 40 the seam of the goods is internally lined up and into a crease-formation.

2. A drying and shaping structure for 45 treating moistened "full-fashioned" hosiery comprising a hollow form to contain a heating medium and having sides which converge to a crease-forming edge at its front portion to crease the front of the goods, the opposite edge being approximately flat to 50 present a seam-engaging surface of a width less than the thickness of the form but greater than that of the crease-forming edge whereby the seam of the goods is lined up internally and set with a crease-formation 55 opposite the crease in the front of the goods.

In testimony whereof I affix my signature in presence of two witnesses.

JOSEPH G. PROSSER.
